UNITED STATES PATENT OFFICE.

FRANK S. SMALLWOOD, OF INDIANAPOLIS, INDIANA.

COUNTERBALANCED CELLAR-DOOR.

1,218,328.

Specification of Letters Patent.

Patented Mar. 6, 1917.

Application filed December 20, 1915. Serial No. 67,887.

To all whom it may concern:

Be it known that I, FRANK S. SMALLWOOD, a citizen of the United States, residing at Indianapolis, in the county of Marion and State of Indiana, have invented certain new and useful Improvements in Counterbalanced Cellar-Doors, of which the following is a specification.

The object of this invention is to hinge 10 cellar doors in such a manner that the liability of breaking the hinges or of unduly straining them when the doors are thrown full open, is obviated, and a further object is to so counterbalance the doors that they 15 may be opened and closed with but little exertion on the part of the operator.

In addition to the above, the object is to provide a strong and durable construction throughout, and also one which will have no 20 projecting hinges or other parts to trip pedestrians when the doors are located in a sidewalk, as is often the case.

I accomplish the above, and other objects 25 which will hereinafter appear, by the mechanism illustrated in the accompanying drawings, in which—

Figure 1, is a top plan view of my invention with the doors closed; the frame members being shown in dotted lines and a portion 30 of one of the doors being broken away to show the parts below. Fig. 2 is a vertical section on the line 2—2 of Fig. 1, and Fig. 3 is a fragment showing the manner of attaching the counterweights.

Like characters of reference indicate like parts throughout the several views of the drawings.

Resting upon a wall 4 of masonry of any usual and suitable construction is a frame 40 5 preferably formed out of metal angle-bars which fit the walls in the manner as is clearly shown in Fig. 2, and riveted upon the two longitudinal or side members of this frame are the metal plates 6, 6, which project inwardly of the inner walls of the frame, in the manner shown, forming an overhanging edge along each inner side of the frame, under which the outer edges of the doors contact in the closed positions of the latter, and which act as stops for the doors in their raised positions.

The doors 7, 7, are similarly constructed, that is, each is comprised of a flat outer metal plate to the under side of which a

smaller frame 8, formed out of angle-bars, 55 is riveted in the manner shown. These two doors are hinged adjacent to their outer edges by rods 9, 9, which extend longitudinally of the doors, passing through the projecting members of the respective frames 8, 60 at the ends of the latter, and also through the vertical members of the frame 5 at the ends of said frame 5, where the rods will be held from longitudinal displacement by a cotter pin 10 or the like. A washer 11, will 65 generally be interposed between the frames 5 and 8 to take up any looseness. The doors will preferably be longer than the length of the opening in frame 5, so they will overlap said frame at each end of the latter and be 70 supported by the frame when the doors are closed. This overlap, however, cannot extend to those portions adjacent the hinges which swing downwardly within the frame during the opening of the doors. The door- 75 plates are therefore cut away as shown and the resulting spaces are filled, when the doors are closed, by plates 12 which are riveted to the frame 5. A plate 13 riveted to one of the doors, overlaps the other door 80 when the doors are closed.

Riveted to the door plates close to the outer edges of the plates are the hinge members 14, to which weight-supporting bars 15—two for each door—are hinged as shown 85 in Figs. 2 and 3, and from each pair of bars per door, a weight 16 is suspended, here shown as by passing the bars 15 through suitable holes in the member 16, and retaining the bars by a nut or cotter pin, as shown. 90 The weights will be regulated to nearly but not quite balance the doors, whereby they will remain closed when placed in that position but may be raised and opened with very little exertion on the part of the operator. 95

The great simplicity of my invention is such that its operation will be obvious without further explanation.

While I have described my invention with 100 more or less minuteness as regards details of construction and arrangement, and as being embodied in certain precise forms, I do not desire to be limited thereto unduly or any more than is pointed out in the claim. 105 On the contrary, I contemplate all proper changes in form, construction and arrangement, the omission of immaterial elements

and the substitution of equivalents as circumstances may suggest or necessity render expedient.

I claim:

- 5 The combination with a cellar door-frame of angle iron with one flange laid horizontally and the other depending vertically therefrom, and an inside overhanging member, of a door comprising an outside plate and a frame of angle iron riveted to the inner side of said plate, a rod extending across the door through said last frame and having its ends journaled in the depending

flange of said first frame, a pair of weight-suspending bars hinged to the door plate 15 between said hinge rod and the adjacent edge of the door which is parallel with the rod, near the rod, and a weight connecting the two bars and removably secured thereto approximately counterbalancing the weight 20 of the door.

In witness whereof I have hereunto set my hand and seal at Indianapolis, Indiana, this 30th day of November, A. D. one thousand nine hundred and fifteen.

FRANK S. SMALLWOOD. [L. s.]
